DESIGN FOR A TEXTILE FABRIC

David Stapler, Philadelphia, Pa.

Application April 17, 1948, Serial No. 145,785

Term of patent 3½ years

(Cl. D92—1)

To all whom it may concern:

Be it known that I, David Stapler, a citizen of the United States, residing at Philadelphia, in the county of Philadelphia and State of Pennsylvania, have invented a new, original, and ornamental Design for a Textile Fabric, of which the following is a specification, reference being had to the accompanying drawing, forming part thereof, in which the figure is a plan view of a textile fabric, showing my new design.

I claim:

The ornamental design for a textile fabric, as shown.

DAVID STAPLER.
